(57) **CLAIM**

The ornamental design for a grow light with stand, as shown and described.

DESCRIPTION

FIG. 1 is a front perspective view of a grow light with stand, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines showing in the drawings are for the purpose of illustrating portions of the grow light with stand and form no part of the claimed design.
